Patented Nov. 1, 1921.

Application filed February 21, 1921. Serial No. 446,957. Term of patent 3½ years.

To all whom it may concern:

Be it known that I, MORRIS PRINCE, a citizen of the United States, and resident of the city of New York, county of New York, and State of New York, have invented a new, original, and ornamental Design for a Hat-Lining, of which the following is a specification, reference being had to the accompanying drawing, forming part thereof, in which—

Figure 1 is a face view viewed from the inside of a hat lining made according to our new design; and

Fig. 2 is a sectional elevation thereof taken along line 2—2 of Fig. 1.

The label shown is of the type usually placed on the inside of the hat and forms no part of this design, the dominant feature of which are the fluted walls.

I claim:—

The ornamental design for a hat lining as shown and described.
